UNITED STATES PATENT OFFICE.

WILBER F. CORNELIUS, OF MUNCIE, INDIANA, ASSIGNOR, BY MESNE ASSIGNMENTS, TO THE VICTOR ADJUSTABLE TRUCK ROLLER SKATE COMPANY, OF SAME PLACE.

ROLLER-SKATE.

SPECIFICATION forming part of Letters Patent No. 325,161, dated August 25, 1885.

Application filed June 28, 1884. (Model.)

To all whom it may concern:

Be it known that I, WILBER F. CORNELIUS, a citizen of the United States, residing at Muncie, in the county of Delaware and State of Indiana, have invented a new and useful Improvement 5 in Roller-Skates, of which the following is a specification, reference being had to the accompanying drawings.

My invention relates to improvements in 10 roller-skates; and the objects of my invention are to facilitate the adjustment of sizes, to improve the scientific movement, and to construct a durable and inexpensive roller-skate. I attain these objects by the mechanism illustrated by the accompanying drawings, in 15 which—

Figure 1 is a longitudinal side view. Fig. 2 is a bottom view; and Fig. 3 is a longitudinal section of my skate, cut through the center on 20 the line *xx*. Fig. 4 is a view of the under side of the front end of my skate-bottom. Fig. 5 is a perspective view of the toe plate casting, 25 pivot-plate, and hanger mechanism, with the wooden bottom removed. Fig. 6 is a view of the tension-screw and cap-plate. Fig. 7 is a view of the lock pivot-plate and hanger detached. Fig. 8 is a perspective view of the 30 hanger, axle, screw, and washer; and Fig. 9 is a view of the slotted heel-plate casting.

Similar letters refer to similar parts throughout the several views.

The skate-bottom *A* is made of wood of the desired size and shape, and at the rear end is secured a heel-casting, *F*, by rivets passing 35 through the bottom *A* and holes *r*. Said casting is made in such a shape as to form a reception for a shoe-heel, and clamping the wood on each side at *v*', so as to prevent it from splitting. In the under side of the said casting there are two slots, *v*', made parallel with 40 each other, as shown in Fig. 9. In the said slots the upper rear part of the heel pivot-plate is secured by lugs formed on the upper part of the said plate *D*, (the same as those seen at *E*' in Fig. 5.) The said lugs are placed 45 in the slots by turning them a little sidewise, and then the front end of the plate is secured to the bottom by a screw, *g*, as shown in Figs. 1, 2, and 3.

The rear pivot-plate is the same shape as the

front one, (which is shown clearly in Figs. 5 and 7,) except that the slotted projection *g*" on the front one is not so long in the rear plate, *D*. The said pivot-plates are each provided with two downward projections on angles of 55 about forty-five degrees, one forming the pivot *i*", and the other a lug, *n n'*, the two forming a recess in which the rubber cushion is placed and a reception for one end of the tension-cap *b b'*.

The hanger is placed on the pivot *i*" on an incline, as shown, with the flat surface *t*' and the ends *t* next to the rubber *d d'*. The tension-cap *b* is then placed in position by a screw, *i i'*, being inserted in the end of the pivot *i*" 65 and through the slot *s*' in said cap. The other end of the cap is provided with a stud, which is inserted in the lower end of the lug *n n'*, as shown in Figs. 1, 2, 3, and 5. When the screw is tightened, it holds the hanger and rubber 70 (movably) in their position.

In Fig. 6 it will be most plainly seen that a set-screw, *a a'*, passes through the plate *d*, and that on the end of the said screw is a small plate which presses against the rubber, and it 75 is secured so that the screw can turn in it but not come out, or in the form of a swivel.

The said screw and plate *b b'* form the tension for the rubber cushion, and by turning the screw the curve or scientific movement of the 80 skate may be made easy or firm, as desired.

The front hanger and tension devices are all the same as the rear. The pivot-plate *E* is also the same, except that the slotted part *g*" is made longer, as heretofore stated and shown. 85

The slotted toe-plate *G* is made similar to the under side of the heel-plate, the slots *G'* are longer, and it is secured to the bottom by rivets *o*', as indicated in Fig. 5.

The front hanger is secured in slots *G'*, the 90 same as the rear hanger, and a nut, *o*, is secured in the bottom *A*, in which a screw, *g*', is inserted, and thereby holds the pivot-plate at any adjustment in the slots. The slotted extension *g*" allows the pivot-plate to be slid 95 backward or forward to adjust the skate to different length shoes, and when the screw *g*' is tightened it holds the plate firmly at any position it is placed.

The axles *k k'* are cast within the hanger, pro- 100

jecting on each side sufficient to pass through the wheels B C. Each end of the axles is provided with a threaded hole, m' , and cut places or notches m , on which the washer e is placed. By the washer having a hole in it just to fit the axle end it cannot turn around, and the screw f is inserted in the hole m' against the washer, holding it firmly, and therefore the backward or forward motion of the wheels can-
10 not work the screw loose or turn the washer.

The adjustment of the front hanger mechanism and wheels backward or forward is sufficient to adapt the skate to several different sized feet.

Having thus fully described my invention, 15 I claim the following as new, and desire to secure the same by Letters Patent:

In a roller-skate, the heel-plate casting F, having slots v' , and secured to the skate-bottom A, said plate binding on the side of the 20 said bottom at v'' , substantially as and for the purpose set forth.

WILBER F. CORNELIUS.
